UNITED STATES PATENT OFFICE.

HENRY J. WICHMAN, OF ST. LOUIS, MISSOURI.

MEASURING-PUMP.

937,198.

Specification of Letters Patent. Patented Oct. 19, 1909.

Application filed March 1, 1909. Serial No. 480,616.

To all whom it may concern:

Be it known that I, HENRY J. WICHMAN, citizen of the United States, residing at St. Louis, State of Missouri, have invented certain new and useful Improvements in Measuring-Pumps, of which the following is a full, clear, and exact description, reference being had to the accompanying drawings, forming a part hereof.

10 My invention has relation to improvements in measuring-pumps; and it consists in the novel details of construction more fully set forth in the specification and pointed out in the claims.

15 In the drawings, Figure 1 is a combined side elevation and vertical section of the pump on the line 1—1 of Fig. 8; Fig. 2 is a vertical sectional detail on line 2—2 of Fig. 1 taken through the hollow rack-bar; Fig. 3 20 is a cross-section on line 3—3 of Fig. 1; Fig. 4 is a vertical section on line 4—4 of Fig. 3 with the arresting stem of the indicator disk however, shoved inward and turned ninety degrees; Fig. 5 is an inner end view of Fig. 25 4; Fig. 6 is an enlarged side view of the tappet-head or lug formed on the bracket which supports the oscillating rack segments; Fig. 7 is a face view of Fig. 6; Fig. 8 is an enlarged top plan of the pump; Fig. 30 9 is a vertical transverse section of the pump-cylinder on the line 9—9 of Fig. 8; and Fig. 10 is a face-view of the rack-bar, shown broken.

The object of my invention is to construct 35 a pump primarily adapted for dispensing oil, kerosene, gasolene and the like (though applicable to pumping all kinds of liquids) in which the stroke of the piston shall be regulated according to the volume or quantity 40 of liquid to be dispensed, such stroke corresponding to standard liquid units such as pints, quarts, half gallons and the like though easily modified for liters and fractions thereof.

45 The purpose is to construct a pump which while not new in principle, shall possess details which render the device susceptible of ready and quick adjustment; one which may be locked against the danger of being tampered with by unauthorized persons, and one possessing further and other advantages better apparent from a detailed description thereof which is as follows:—

50 Referring to the drawings, B, represents a suitable base to which is bolted or tied the pump-cylinder C in the usual way, the cyl-

inder being provided with a discharge pipe d leading from the upper wall thereof, said pipe terminating in a discharge spout n of well known construction, the passage thereof being controlled by a spring-actuated valve r which is unseated by the pressure of the liquid as it discharges, and automatically closes or seats under the action of the spring s when the discharge discontinues. The hollow base B has suitable provision for screwing thereto a pipe p, leading down to the source of liquid supply, an intake check-valve a being positioned above the point of attachment t for the inlet pipe. The piston 1 of the pump-cylinder has a check-valve 2, the piston-rod 3 passing through a stuffing-box 4 in the top of the cylinder and connecting outside of the cylinder with a rack-bar 5. The rack-bar is formed in cross-section as shown in Fig. 3, being substantially an open bar with diverging walls 5, 5, having toothed edges, the walls 5, 5, thus forming a housing or chamber 6 between them. Disposed along the closed wall or face of the rack-bar are a series of indicator disks or buttons 7, having marks, 1 pt., 1 qt., 1½ qts., ½ gal. to indicate the quantity of liquid to be dispensed or quantity drawn into the pump cylinder for a given length of piston stroke. Each button is fastened to the outer end of a stem 8 loosely mounted in the rack-bar, the stem operating in a hollow plug or bearing 9 which receives the stem, the plug being adjustable vertically along an elongated slot or opening o formed in the rack-bar, and when once adjusted is tightly clamped to the bar by a nut 10 passed over the plug, the latter having a shoulder m for engaging the inner face of the rack-bar when the parts are tightened. The inner end of the plug 9 is recessed or forked, the recess r being comparatively narrow, (Fig. 5). The inner end of the stem 8 is provided with a cross pin 11 which under the action of the expanding spring i (interposed between the head 7 and rack 5) is drawn into the base of the recess for an outer position of the stem and button (Fig. 3) the inner end of the stem under the circumstances coming flush with the inner end of the plug. By pushing the button and stem inwardly until the pin 11 has passed beyond the end of the plug, and then giving the stem a turn of ninety degrees, the pin 11 will engage the end of the plug and thus hold the stem projecting beyond the plug as shown in Figs. 4 and 5. Any one

of the stems may be thus temporarily set, and this for a purpose presently to appear. When thus shoved inwardly, the stem with any upward stroke of the piston will strike 5 the base of a tappet rib or block 12 formed or cast with the arm 13 of the supporting bracket or standard S. The rack-bar and piston are actuated by the oscillating toothed arcs or segments 14, 14 pivoted to the bracket 10 S on each side of the arm 13 and meshing with the toothed portions of the rack-bar. The forked operating handle H is coupled directly to the segments 14.

Formed in the tappet block 12 is a trans- 15 verse recess or groove in which operates a sliding bolt 15 held against displacement or loss by a cover-plate 16 secured and shou- 20 dered to the block, the plate being provided with a key-hole h (Fig. 7) for receiving a key K inserted through an opening h' in the rack-bar, the end of the key engaging a notch e in the bolt and shifting it in proper direction (with the turning of the key) to cause it to engage an opening o' formed in 25 the adjacent wall of the rack-bar. The bolt when thus forced into the opening o' locks the rack-bar to the block 12 (and its arm 13) thus locking the rack-bar against movement should an attempt be made by un- 30 authorized persons to operate the pump. Any kind of key or bolt may be employed, that here illustrated being a conventional one. The bolt is held in place by a spring 17 dropped into a socket of the block 12 the 35 spring being kept confined by a screw plug 18 as shown.

The operation may be described as follows: Assuming the handle to be in its lowest position in which case the piston 1 will be 40 at the bottom of the pump-cylinder (it being of course understood that the cylinder has been previously pumped full by a few strokes of the piston) and supposing the operator wishes to dispense say 1½ quarts 45 of the oil or other liquid. He thereupon pushes in the indicator button 7 and its stem 8 as shown in Fig. 4 whereupon with an upward oscillation of the handle H the rack-bar 5 and the piston 1 are drawn upward, 50 the oil from the pipe p following the ascending piston. When the inner projecting end of the indicator stem 8 comes in contact or strikes the base of the tappet rib 12 the stroke of the piston is arrested, and only 55 that quantity of liquid which corresponds to the particular length of stroke of the piston will be delivered through the spout n. In Fig. 1 the third button with its stem has been shoved inward, so with any given 60 upward stroke one and one-half quarts of oil are dispensed. If the customer desires only a pint, then the third stem is released, and the top stem of the series is pushed in. The only stem which strikes the rib 12 is the 65 one which has been shoved in, the remaining

stems of the series readily clearing the tappet rib. Each clerk may carry a key and lock the parts against movement by unauthorized persons by shoving the bolt 15 into the opening o' of the rack bar 5 when 70 the latter can not be moved from its locked position until again released by the next clerk having occasion to use the pump. In lieu of a rack and pinion connection between the piston and segments 14, any equivalent 75 gearing may be substituted as obvious to the skilled mechanic. Of course, the pump and pump valves are well known, nothing novel being claimed for the pump proper.

Having described my invention, what I 80 claim is:—

1. In combination with a pump cylinder having a reciprocating piston provided with a rod, an indicator movably coupled to the piston-rod of said piston, a tappet for intercepting the indicator and thereby arresting further movement of the piston, and means for shifting the indicator to clear the tappet.

2. In combination with a pump-cylinder having a reciprocating piston provided with 90 a rod, a series of indicator devices mounted on the rod and spaced apart, said devices being adjustable horizontally, and a stationary arresting tappet positioned in the path of the vertical travel of said devices when they 95 are adjusted in one position and adapted to be cleared by said devices when they are not so adjusted.

3. In combination with a pump-cylinder having a reciprocating piston, a rack-bar 100 connected thereto and projecting outside of the cylinder, a stationary tappet, a series of indicator devices composed of stems disposed along the rack-bar and independently adjustable to and from the tappet whereby any 105 stem may be set to be impinged by the tappet for a movement of the piston in one direction and thereby arrest the piston.

4. In combination with a pump cylinder having a reciprocating piston, a rack-bar 110 connected thereto, a supporting bracket, a pair of oscillating segments mounted on the bracket and engaging the rack-bar, a tappet block or rib on said bracket, a series of indicator devices carried by the rack-bar and 115 adapted to be intercepted by the tappet block aforesaid, and means on the tappet block for interlocking with the rack-bar and prevent movement of the piston in either direction.

5. In combination with a pump cylinder, 120 a reciprocating piston, a chambered rack-bar coupled thereto, a series of rotatable stems secured to the face of the rack-bar, an outer terminal button for each stem, a hollow plug for each stem provided with an inner terminal recess, a pin on the stem adapted to span the recess upon a partial turning of the stem, the latter being movable longitudinally in the plug, a spring interposed between the plug and its button, a stationary arm, a tap- 130

pet or impact block on the arm projecting into the chamber of the rack-bar and adapted to arrest a stem, and oscillating toothed segments meshing with the teeth of the rack-bar.

6. In combination with a pump cylinder, a piston, a chambered rack-bar coupled to and operating said piston, a rigid arm, a key-operated sliding bolt on the arm, the outer wall of the rack-bar having a key-hole or opening, and a second opening for the reception of the bolt carried by the arm, whereby upon shifting of the bolt the bar becomes locked to the arm.

7. In combination with a reciprocating

rack-bar, a stationary support, a series of rotatable spring-controlled stems distributed along the rack-bar, means for shifting the stems longitudinally in directions transverse to the axis of the rack-bar whereby for an inward movement of the stems the same may be brought into position to impinge against the stationary support, and for an outward movement thereof may clear said support.

In testimony whereof I affix my signature, in presence of two witnesses,

HENRY J. WICHMAN.
